SIEGMUND STRAUSS, OF VIENNA, AUSTRIA

CURRENT RECTIFIER

Application filed June 26, 1929, Serial No. 373,877, and in Austria May 19, 1927.

The invention relates to a current rectifier of the kind employed in connection with electric measuring apparatus and for other purposes, especially where condensers are to be charged from a supply and constant voltage is required in spite of any fluctuation of the voltage of this supply. A current rectifier of the kind to be described in the following is adapted for feeding a condenser forming part 10 of the measuring apparatus, which is for instance repeatedly charged from the supply and is discharged through an ionic chamber or other high resistance, the value of which is to be measured. The frequency of the condenser discharges within a certain time depends on the resistance to be measured and on the voltage up to which the condenser is charged. For exact measurement therefore constant voltage must be applied to the condenser by the repeated charges, because otherwise no correct result would be obtained if the condenser voltage would be affected by every change of the supply voltage.

According to the invention a constant voltage is obtained by deriving it from the terminals of a condenser forming part of the rectifying apparatus charged continuously by means of a thermionic or rectifying valve and by discharging the condenser at the same 20 time through another thermionic valve, whereby in the arrangement according to the invention influences of varying supply voltage are eliminated in a manner, which will be more fully described later and exact measurement will be secured.

The arrangement according to the invention may be as well employed for other than measuring purposes as for instance for high voltage rectifying in connection with apparatus for Roentgen rays, cable testing sets and the like, wherein a constant value of continuous voltage is to be maintained unaffected by any fluctuation of the supply voltage.

The object of the invention is shown in the accompanying drawings, wherein

Fig. 1 shows a connection of a measuring apparatus according to the invention,

Fig. 2 shows a similar but modified arrangement, wherein the valve employed is connected in a somewhat different manner.

Fig. 3 shows another arrangement, wherein constant voltage is obtained.

Referring to Fig. 1 A and B are thermionic valves with heated filaments F and F' inversely connected in series with a condenser 55 K to a source Q of alternating current, the derived voltage of which is to be held constant, that is one terminal N of the source of alternating current is connected to the plate P of valve A and at the same time to the 60 heating filament F' of valve B and vice versa, the terminal N' with the plate P' of valve B and the filament F of valve A. As is shown by Fig. 1 the filaments F and F' are heated by means of suitable transformers T and T' 65 and adjustable resistances R and R' from the source and the filament F of valve A is preferably heated to a somewhat higher degree so that the electrons are emitted in accordance with the actual voltage applied to the plate 70 P, whereas the valve B, its filament F' being subjected to a weaker heating, is working below saturation so that the current of the plate P' essentially depends on the heating effect.

If for instance the supply voltage increases the emission in valve A likewise increases. In valve B, however, it increases to a much higher degree. The charge of the condenser K thereby is carried away more rapidly and by adjusting the heating effect a practically constant voltage on the condenser K may be obtained in an easy way. The arrangement of Fig. 1 being completely symmetrical it is possible to impart the inverse polarity to the condenser by varying the adjustable resistances R and R' of the heating 80 circuits.

Fig. 2 shows a similar connection in which the condenser K is connected between the filament F' and the plate P' of the valve B 90 instead of being connected to the supply Q. The arrangement therefore is not symmetrical and the polarity of the condenser K is invariable. The valve A must not necessarily be provided with a heated filament 95 whereas this must be the case with valve B.

In another modification constant voltage, where only very small current is required is obtained by connecting two rectifying valves by way of two condensers in series, one 100

- of which is of extremely high insulation and by deriving rectified current from the terminals of the condenser, which is insulated as usual, its voltage being affected by the fluctuations of the voltage of the main supply, whereas from the other condenser with extremely high insulation, a small amount of constant current is supplied under nearly constant voltage, unaffected by fluctuations.
10. This modification is shown by Fig. 3.
11. A transformer T is connected to the supply mains having a primary winding U and four secondary circuits V, V' and W, W' two of them V, V' serving for heating the filaments of the rectifying valves C, D and the two other windings W, W' for supplying alternating current which is converted into continuous current. A continuous current is derived either from the terminals L, O of the condenser K, or from the terminals O, Z of the condenser K₂. The plates of the valves are connected to a neutral O and to one armature of either of the condensers K₁ and K₂. According to the invention the condenser K₂ is made with extremely high insulation, whereas the condenser K₁ is built up as usual. Then if the current supplied from the condenser K₂ is negligible the voltage on condenser K₂ remains unaffected by any variation of the supply voltage.

What I claim is:—

1. A current rectifier adapted to be connected with measuring apparatus for high resistances and ionic currents in which a condenser is employed repeatedly charged up to a constant voltage, said rectifier comprising a condenser charged by way of a rectifying valve from a supply of current, another thermionic valve connected as a discharge path by which part of the condenser charge is carried away in dependence of the actual voltage value of the supply, this dependence resulting from heating the filament of the thermionic valve from the supply.
2. A current rectifier according to claim 1, wherein the valves are arranged symmetrically and connected to the supply in parallel to each other and with the condenser in series, whereby the polarity of the condenser is adapted to be reversed by adjusting the heating current.
3. A current rectifier according to claim 1, wherein one of the valves is connected to the supply in series with the condenser.

55. In testimony that I claim the foregoing as my invention, I have signed my name.

SIEGMUND STRAUSS.
